UNITED STATES PATENT OFFICE

2,471,357

RAILWAY SWITCH

Harry R. Smith, Wilkinsburg, Pa., assignor to
The Union Switch & Signal Company, Swiss-
vale, Pa., a corporation of Pennsylvania

Application July 16, 1946, Serial No. 683,885

1 Claim. (Cl. 246—438)

1

My invention relates to railway switches, and particularly to railway switches in which the movable switch points are resiliently supported through the medium of roller bearings to reduce friction while the switch is being thrown.

To provide the best operation of switches of the type described it is desirable that the roller bearings should support about 80% of the weight of the switch points and their connections, the remainder of the dead weight and the weight of passing trains being carried by the usual riser plates. The weight of the switch points varies considerably with the length of the switches, the degree of wear of the switches, the type of connections employed, the rail size, etc., and it follows therefore that in order to obtain the desired operative relation between the roller bearings and the switch points it is necessary to be able to readily adjust the resilient means which supports the roller bearings in a manner to vary the amount of support provided to the switch points by the roller bearings.

One object of my invention is to provide novel and improved means for accomplishing this result.

According to my invention, each switch point which is to be resiliently supported has attached to its under side a roller plate which extends underneath the adjacent stock rail, and which rides on a roller bearing mounted in the inner end of a cantilever type supporting bracket, the outer end of which bracket is attached through the medium of compression springs, and bolts for adjusting the initial compression of the springs, to a spring bracket bolted to the outer side of the stock rail.

Other objects and characteristic features of my invention will become apparent as the description proceeds.

I shall describe one form of railway switch provided with a roller bearing embodying my invention, and shall then point out the novel features thereof in claim.

In the accompanying drawings, Fig. 1 is a top plan view showing a portion of a railway switch point supported by a roller bearing in accordance with my invention. Fig. 2 is a vertical sectional view taken substantially on the line 2—2 of Fig. 1. Fig. 3 is a sectional view taken on the line 3—3 of Fig. 2.

Similar reference characters refer to similar parts in all three views.

Referring to the drawings, the reference characters 1 and 2 designate respectively one of the movable switch points and the adjacent stock

2

rail of a railway switch of the usual and well-known construction. The stock rail 2 is supported on riser plates 3 secured to cross ties 4 in the usual manner, and the switch point 1 is intended to be moved toward and away from rail 2 by any of the usual switch throwing devices, not shown.

Secured to the under side of the switch point 1 in any convenient manner, as by welding, is a roller plate 5 which extends underneath the stock rail 2, and the smooth bottom surface of which rides on a roller bearing 6 mounted in the inner end of a bearing supporting bracket 7. The portion of the roller plate 5 which extends underneath the rail is provided with a notch 5a the depth of which may be varied if necessary to meet the varying thicknesses of riser plates and weights of switch points.

The bearing bracket 7 is of the cantilever type, and extends transversely underneath the switch point 1 and stock rail 2 below the roller plate 5 and is provided at the opposite sides of the plate 5 with two vertical ribs 7e which cooperate with the bracket 5 to maintain the bracket in vertical alignment with the plate 5. The bracket 7 is also provided at its outer end with a vertical surface 7a, with two vertical ribs 7b disposed at the opposite sides of the surface 7a, and with a laterally projecting lip 7c disposed at the upper end of the surface 7a. The lip 7c extends into a depending portion 8a formed on a spring supporting bracket 8 bolted by means of bolts 9 to the outer side of the stock rail 2, and engages the upper ends of two coil springs 10 which surround the bolts 11 between the lip 7c and a spring plate 12 mounted on the lower ends of the bolts. The bolts 11 extend upwardly with clearance through holes 7d provided in the lip 7c and through aligned holes 8b formed in a horizontally

extending portion 8c of the bracket 8, and are provided above the horizontally extending portion 8c with a spring lock washer 13, a spring compression nut 14, and a lock nut 15. The depending portion 8a of the bracket 8 is rounded so as to form with the vertical portion 7a of the bracket 7 a housing for the springs 10, the lower end of which housing is closed by the spring plate 12. The sides 8d of the depending portion 8a of the spring bracket 8 fit between the ribs 7b in a manner to maintain the bearing bracket 7 in a vertical position and are provided at their right-hand ends with vertical surfaces 8e which serve as guides for the bearing bracket when the bracket is depressed due to a load on the switch point 1.

With the parts arranged in the manner described, it will be apparent that the roller 6 will act through the medium of roller plate 5 to exert on the switch point 1 an upward force which depends upon the amount of compression of the springs 10, and that the amount of compression of the springs 10 can readily be adjusted by first loosening the lock nut 15 and then screwing the adjusting nut 14 in one direction or the other. As was pointed out hereinbefore, in actual practice it is usually desirable that the upward force exerted by the roller 6 on the switch point 1 should be sufficient to support about 80% of the weight of the switch point and the associated switch point connections, and the nuts 14 will usually be adjusted to provide this degree of support. It will be obvious, of course, that since a large part of the weight of the switch point 1 is supported by means of roller 6 the amount of friction which exists when the switch point 1 is reversed will be very materially reduced, thus reducing the force required to reverse the switch point.

One advantage of a roller bearing assembly for supporting a switch point constructed in accordance with my invention is that the nuts 14 provide micrometer adjustment for varying switch point loads and are located in a position where they are readily accessible.

A further advantage of a roller bearing assembly constructed in accordance with my invention is that it is readily applicable to different rail shapes and sizes and different switch point lengths.

A further advantage of a roller bearing assembly constructed in accordance with my invention is that since the roller plate 5 extends underneath the main stock rail 2 the switch point 1 is always maintained in proper operative position with respect to the main stock rail 2 regardless of the amount of lifting force that is exerted by means of the roller bearing assembly.

A further advantage of a roller bearing assembly constructed in accordance with my invention is that all parts are enclosed so that they are in effect protected from the weather, dirt, dust, etc.

Although I have herein shown and described

only one form of roller bearing assembly for application to railway switches, it is to be understood that various changes and modifications may be made therein within the scope of the appended claim without departing from the spirit and scope of my invention.

Having thus described my invention, what I claim is:

The combination with a railway switch comprising a track rail and a switch point movable toward and away from the rail, of a spring bracket secured to the outer side of the rail and provided with a laterally projecting portion terminating in a depending portion having curved ends, two spring bolts extending with clearance through holes provided in said laterally projecting portion and provided above said laterally projecting portion with nuts, a spring plate mounted on the lower end of said bolts, coil springs surrounding said bolts between said spring plate and said laterally projecting portion, a rigid cantilever member extending underneath said switch point and said switch rail and provided at its outer end with a lip having formed therein holes that receive said bolts between said springs and said laterally projecting portion and with a vertical portion which cooperates with said depending portion to form a housing for said springs, a roller journaled in the inner end of said cantilever member, and a roller plate secured to the under side of said switch point and extending underneath said rail and riding on said roller, said adjusting nuts being adjusted to compress said springs sufficiently to cause said roller to partially support said switch point.

HARRY R. SMITH.
